DESIGN FOR A LACE

Bert Edson, Pawtucket, R. I.

Application July 6, 1936, Serial No. 63,677

Term of patent 3½ years

To all whom it may concern:

Be it known that I, Bert Edson, a citizen of the United States of America, residing in Pawtucket, county of Providence, and State of Rhode Island, have invented a new, original, and ornamental Design for a Lace, of which the following is a specification, reference being had to the accompanying drawing, forming part thereof,

The figure of the drawing is a plan view of a Lace embodying my new design.

The design unit is contained between the broken lines, which unit is repeated in regular succession as indicated by the extensions beyond the unit boundaries.

I claim:

The ornamental design for a lace substantially as shown and described.

BERT EDSON.
